[57] CLAIM

The ornamental design for a combined suction cleaner upper housing and bag or the like, as shown and described.

DESCRIPTION

FIG. 1 is a left front perspective view of the combined suction cleaner upper housing and bag or the like showing my new design;

FIG. 2 is a right side elevational view thereof;

FIG. 3 is a rear elevational view thereof;

FIG. 4 is a top plan view thereof; and

FIG. 5 is a bottom plan view thereof.

The broken line disclosure of FIG. 1 is for illustrative purposes only and forms no part of the claimed design.

FIG. 2

FIG. 3
